PUMP APPARATUS

George K. Williams, Rte. 1, Box 121-A,
Mobile, Ala. 36605
Filed Feb. 3, 1967, Ser. No. 613,772
5 Claims. (Cl. 103—262)

ABSTRACT OF THE DISCLOSURE

The invention comprises a bilge water ejection device for a boat including a venturi pump located below the transom of the boat and a vacuum line leading into the boat over the transom thereof, having a ball valve within the vacuum line to prevent a backflow siphoning of water into the boat when the boat is at rest.

This invention relates to fluid pumps generally, and more particularly to an improved bilge water ejection apparatus for boats and the like characterized by lack of moving parts, means permitting removal of the invention from the boat, and secondary utility as a siphon device.

This application is a continuation-in-part of my application Ser. No. 549,652, filed May 12, 1966, now abandoned.

The invention has particular utility with small pleasure craft which have increased a hundredfold in numbers in recent years, and can be found in almost any body of navigable water in the country. With the increased numbers of boats has come the inevitable diversity of types of craft and of modes of construction and use. However, one problem still seeks a satisfactory solution. This problem is removing water in the interior of the boat, accumulated either through leakage or rainfall, quickly, efficiently, and at minimum cost. The present invention overcomes the problem by providing a bailing device that is completely self-contained, portable, and maintenance free. The invention may be attached to a boat without need of any modification of the boat whatsoever. Further, the invention needs no power source other than water passing beneath the boat, and will not interfere with any propulsion or steering means used with the boat, or with any trawling device used from the boat. Finally, the invention may be used as a siphon for removing accumulated water in the boat while the boat is on a trailer on land.

In the preferred embodiment, the invention comprises a venturi pump apparatus located directly beneath the transom of the boat, a first, rigid vacuum line operatively connected to the vacuum inlet of the venturi, a second, flexible inlet line connected to the free end of the first line which extends to the interior bottom of the boat, where water collects, a bracket assembly attached to the invention at the junction of the first and second lines for removably securing the invention to the transom of the boat, and a ball valve assembly within the first rigid line to prevent backflow siphoning into the boat when the boat is at rest in the water.

Further and more complete objects and advantages of the invention may be had by reference to the following specification and drawings in which:

FIGURE 1 is a side elevational view of the invention, showing the same attached to the transom of a boat (shown in partial section);

FIGURE 2 is a detail, elevational view of the upper portion of the invention as shown in FIG. 1, drawn to an enlarged scale;

FIGURE 3 is a sectional view taken along lines 3—3 of FIG. 2;

FIGURE 4 is a detail, elevational view of the lower

2

portion of the invention as shown in FIG. 1, drawn to an enlarged scale;

FIGURE 5 is a detail view of the end of the inlet line, shown resting on the interior bottom of the boat in FIG. 1; and

FIGURE 6 is a sectional view taken along lines 6—6 of FIG. 4.

Referring now to the invention by reference characters and in particular to FIG. 1 thereof, the invention is shown comprising a venturi pump 10, situated immediately to the rear of transom 12 of boat 14, and immediately beneath the rear, bottom edge of hull 16, a first, rigid, vertical vacuum line 18, a bracket assembly 20, and a flexible inlet line 22. FIGURE 4 indicates that the venturi 10 includes an entry port 24 having a jet opening 26 and a jet nozzle 28 formed therein, an intake 30 for vacuum line 18, and an elongated discharge tube 32. Venturi 10 operates in the usual manner, in that when boat 14 is being propelled through water (propulsion means not shown), water under pressure will enter entry port 24, due to its location beneath the hull 16. The water enters jet opening 26, where the velocity of the water is increased due to the decreasing internal diameter of the jet opening from the entry port 24 to the jet nozzle 28. Water emitted from jet nozzle 28 will create a negative pressure potential in chamber 34, around and behind nozzle 28. This potential is utilized by forming intake 30 for line 18 in venturi 10, adjacent chamber 34.

In order to permit use of the invention with several different boats, and to permit easy attachment and removal of the invention, venturi 10 is not attached directly to the boat, but is maintained in proper position by the inflexibility of vacuum line 18, line 18 being secured to the boat through bracket assembly 20.

Bracket assembly 20 includes an inverted U-shaped base member 36, which is attached to transom 12 by suitable means such as a pair of clamping screws 38, 38, an L-shaped support plate 40 for lines 18 and 22, and a spring loaded pivot mount 42 on base 36 for plate 40. Pivot mount 42 includes a first pair of ears 44, 44 on base 36, a second pair of ears 46, 46 depending from L-shaped plate 40, aligned bores through both pairs of ears to receive a pivot shaft assembly 48, and a torsion spring 50 (FIG. 3) mounted on shaft 48 to plate 40, urging plate 40 rearwardly and downwardly with respect to transom 12. Line 18 is secured rigidly to L-shaped plate 40 by suitable means, such as a pair of clamps 52, 52. Line 18 and venturi 10 are thus pivotally mounted on base 36 so as not to damage the invention should it strike floating or submerged debris in the water. Should venturi 10 strike a foreign object, pivot mount allows the venturi 10 and line 18 to swing upwardly about base 36 to clear the object and prevent damage to the invention.

As indicated in FIG. 2, flexible inlet line 22 is attached to line 18 by a suitable fitting 54. The lower interior end of line 22 is provided with a strainer 56 (FIG. 4) which prevents accumulated debris in the interior of the boat from being sucked into the invention and blocking the operation thereof.

FIGURES 1, 4 and 6 indicate a ball valve assembly including buoyant ball 58, upper valve seat 60, and flange 62 at the base of line 18. Preferably, seat 60 will be located above the water line indicated in FIG. 1 so that the invention will operate even at very slow speeds and to avoid excess water pressure being required to unseat ball 58 from seat 60. Seat 60, which comprises a reduction in the internal diameter of line 18, serves to block backflow of water into the boat when the boat is at rest, aided by ball 58 thereagainst. Flange 62 is provided to retain ball 58 permitting bilge water to escape into discharge tube 32 when the invention is operating. Water pressure

in line 18 will force ball 58 down to the base of line 18, where passage 64 is formed in line 18, internally of flange 62. Passage 64 has a width less than the diameter of ball 58 to prevent ball 58 from blocking the escape of water through flange 62.

As mentioned above, the invention may be used as a siphon to remove accumulated rainwater from the interior of the boat when the boat is on dry land, on a trailer or the like. This is accomplished with the use of a garden hose or other water supply under pressure (not shown) for purposes of priming the invention. Water is introduced through the forward end of entry port 24 until lines 18 and 22 are full. With removal of the hose, water will siphon through the invention, as strainer 56 is situated at a higher position than discharge tube 32. Of course, when the invention is used for bailing purposes and the venturi is employed, priming of the invention is unnecessary, as movement of the boat through water will create a constant vacuum in lines 18 and 22, sufficient to withdraw water from the boat.

The invention may be constructed of various materials, such as metals or plastics. Line 22 need not be flexible, but it is desirable so that strainer 56 may be placed in the lowest interior part of the hull 16. The invention may be constructed in collapsible form so as to fit in a small area when not in use, such as a tackle box. Thus, a fisherman who rents a boat to enjoy the sport of fishing could carry the invention with him to bail the rented boat. Finally, line 22 may be made of several interfitting sections to vary the length thereof so as to accommodate the invention to boats of varying transom height.

It is readily apparent from the foregoing that I have invented a new and highly useful device in the art of bilge water ejection devices, and thus I am not to be limited to the exact construction as hereinbefore provided, except as may be deemed to be within the scope of the following claims.

I claim:

1. A removable bilge water ejection device for use with a boat or the like comprising: a venturi pump operable by movement of said pump through the water, a first rigid vacuum line operatively connected to said venturi pump, a bracket assembly supporting said vacuum line and adapted for clamping engagement with a boat transom or the like, and a second vacuum inlet line operatively connected to the free end of said first line and adapted for communication with a source of bilge water to be ejected, said bracket assembly comprising an inverted U-shaped plate, adapted to fit over said transom or the like, at least one clamping screw extending through one part of said bracket to said transom or the like, a pair of upright ears having aligned bores therein on the top of said bracket, and L-shape support plate adapted

to rest on said bracket, the base of said L-shaped plate positioned generally parallel to and over the upper and rear faces of said U-shaped plate, a second pair of ears having aligned bores therein formed on the under-surface 5 of said L-shaped plate, adjacent said first pair of ears, a central shaft through said bores, both of said pairs of ears securing said plates together, a torsion spring mounted interiorly of said pairs of ears along said shaft urging said L-shaped support plate against said U-shaped plate, and clamp means for securing said first vacuum line rigidly to said L-shaped plate.

2. The device of claim 1 wherein said venturi pump comprises an entry port for water under pressure, supplied by movement of the pump through water, a tapered 15 jet opening formed in said entry port, a jet nozzle at the end of said jet opening, discharge of water through said jet nozzle creating a suction area within said venturi pump, an intake formed in said suction area, and extending upwardly to receive said first vacuum line, and an 20 elongated discharge tube connected to said pump about said jet nozzle and extending rearwardly of said pump for discharge of said water under pressure and said bilge water.

3. The device of claim 1 wherein the free terminal end 25 of said inlet line is provided with a strainer to exclude accumulated debris from said device.

4. The device of claim 1 wherein said inlet line is formed of flexible material.

5. The device of claim 1 including a ball valve assembly 30 within said first vacuum line to prevent backflow siphoning of water, said assembly comprising: a buoyant ball, located within said first line, an upper valve seat for said ball and a lower valve seat including walls adjacent the end of said first line, defining an opening, said 35 opening affording communication between said first line and said venturi pump, said opening being configured to retain said ball while permitting the flow of water.
